COLLECTING MACHINE, PARTICULARLY
FOR GRANULAR MATERIAL

Carl Einar Lundberg, Kiruna, Sweden

Application June 5, 1942, Serial No. 445,955
In Sweden July 20, 1940

4 Claims. (Cl. 198—9)

The object of the present invention is to provide a simple and easily operated collecting or loading machine, particularly for granular material, which is also cheap in operation but of great capacity, and which can be used within very different spheres of work without considerable reconstruction.

Another object of the invention is to provide a machine in which the elements subjected to the most violent wearing are very cheap and easily exchanged.

The above specified and other objects are accomplished, according to the invention, by the arrangement and combination of parts set forth in the following detailed description, defined in the appended claims and illustratively exemplified in the accompanying drawings, in which

Fig. 1 is a side elevation of the collecting machine,

Fig. 2 is a plan view of the same,

Fig. 3 is a plan view of a detail, and

Fig. 4 is a larger scale sectional view of a detail taken on the line IV—IV in Fig. 2.

Referring to the drawings, numeral 1 indicates a vehicle frame carried by wheels 2. In case the vehicle is to be driven over a difficultly trafficable ground the same is preferably provided with endless chains. At one end of the frame 1 two arms 5 are pivoted on a shaft 4, said arms 5 at one end carrying a guide roller 6 for an endless conveying belt 7 as well as two arms 9 united with a ring 8. The other ends of arms 5 are provided with, or formed as, toothed segments 10, which are in mesh with toothed wheels 11 fixed to a shaft 13, the turning of said shaft by means of a crank 12 consequently causing the arms 5 to rock. The latter and the toothed segments 10, of course, may be fixed to the shaft 4, the latter being in such case rotatably mounted. With the ring 8 there are also flexibly united two arms 14, the other ends of which are provided with guide slots 15. Said guide slots are engaged by suitable clamping means 16 secured to the vehicle frame and adapted to fix the arms in the desired position relatively to the vehicle frame.

To the ring 8 there are secured suitably spaced rollers 17 engaging a guide groove 18 in a ring 13 (Fig. 4). The latter is fixed to the underside of a flat plate 20 having a continuously curved outer edge and the outer circumference of the ring 13 is provided with teeth 21, which are in mesh with a motor driven toothed wheel not shown on the drawings. The plate 20, which has a central circular opening 22, is provided on its upper surface with vanes 23, which are arranged at an inclina-

tion to the plate. Each vane 23 extends for a little more than half of its length along the outer edge of the plate 20 and has an inwardly curved portion meeting the opening 22 on a substantially tangential line (Fig. 3). From the drawing it will be clear that the height of the vanes successively decreases towards the outer edge of the plate. In the lower half of the opening of the plate there is provided a chute 24 of semi-circular cross section, which is rigidly secured to the ring 8, and the lower end of which is preferably provided with an elastic downward extension 24a, bearing on the belt 7 or adapted to be pressed against the same.

According to the illustrated embodiment there is a second endless conveying belt 26 carried by a turnable arm 25. By means of a crank 27 and a worm gear 28 said arm 25 may be adjusted to the desired position, whereby the material falling down from the belt 7 on the belt 26 is transported to receptacles behind or laterally of the collecting machine. The conveying belts 7 and 26, the plate 20 and the driving wheels of the vehicle may preferably be driven by the same motor, and they may all be adjusted while the machine is in operation.

The machine operates as follows:

After the machine, with receptacles, if any, connected thereto, has been driven to the place 30 of work, the disc 20 by means of crank 12 is adjusted to a suitable height and by means of the clamping means 16 fixed in a suitable inclining position. (These adjusting means are easily operated even during work, the greatest efficiency 35 of the machine being thereby obtained.) The plate 20 is now put into rotation, and because of the shape of the vanes 23 the machine will, so to say, cut its way into the material in question, which is carried up at a level with the opening 22, into which the material falls down owing to its own gravity. Since the inner ends of the vanes 23, when moving upwards, tightly bear on the outer side of the semi-circular chute 24, which may be provided with an exchangeable 40 fitting, no material can fall back again but is positively carried upwards until it falls down into the opening 22 or on to the chute 24. The downward extension connected with this chute ensures that no part of the material elevated by 45 the vanes 23 can fall down on to the ground, all material being at once conveyed by the belts 7 and 26 to the respective receptacles, the arm 25 being adjusted so that the material falls down into the correct receptacle. The collecting machine may be moved from one place to another

and operating elements may be adjusted without any interruption of the work being necessary.

As already mentioned, the machine is particularly intended for granular material, such as coal, ore, gravel and the like, but it may also be used with advantage for collecting other materials. Thus, it may be used also for peat, the device in this case, if the vanes 23 are suitably shaped, being able to attack the ground directly. Several embodiments are possible, of course, within the scope of the invention, the nature of the material to be collected to a great extent determining in what manner the device is to be modified.

Having now described my invention, what I claim as new and desire to secure by letters patent is:

1. In a collecting machine, particularly for granular material, having a frame, a rotatable flat plate obliquely positioned on said frame, said plate having a continuously curved outer edge and being provided with a central substantially circular opening, a conveyor disposed beneath said opening, the combination of at least one upstanding curved vane on the upper surface of said rotatable plate, said vane extending for approximately half of its length along the outer edge of said plate and having an inwardly curv-

ing portion meeting said opening on a substantially tangential line, and a stationary chute of semi-circular cross-section projecting through the lower half of the opening of said plate, said chute being adapted to catch the material falling down from the plate and to direct it to the conveyor.

2. Collecting machine as claimed in claim 1, in which the height of the vane gradually decreases towards the outer edge of the plate.

3. Collecting machine, as claimed in claim 1, including an elastic downward extension of said chute bearing on said conveyor.

4. In a collecting machine, particularly for granular material, having a frame, a rotatable flat plate obliquely positioned on said frame and carrying curved collector vanes, and an endless belt conveyor beneath a central opening in said plate, the combination of means for rotatably supporting said plate on said frame, said supporting means comprising a circular guide groove provided on the underside of said plate, a ring carrying a plurality of rollers adapted to engage said guide groove for guiding and centering said plate, arms rigid with said ring and adjustably pivoted to said frame, and a guide roller for said endless belt conveyor carried by said arms.

CARL EINAR LUNDBERG.
